UNITED STATES PATENT OFFICE.

WILLIAM S. HUNKINS, OF LOS ANGELES, CALIFORNIA.

HOSE-SUPPORTER.

1,398,488.

Specification of Letters Patent. Patented Nov. 29, 1921.

Continuation of application Serial No. 430,622, filed December 14, 1920. This application filed July 16, 1921. Serial No. 485,380.

To all whom it may concern:

Be it known that I, WILLIAM S. HUNKINS, a citizen of the United States of America, residing at Hollywood Station, Los Angeles, 5 California, have invented a new and useful Hose-Supporter, of which the following is a specification.

My invention relates particularly to a device of the character set forth in my former Patent #1,354,485 of October 5, 1920, and the present application is a continuation of my former application 430,622 filed December 14, 1920, the present application being confined to the subject matter not claimed 10 in my aforesaid application although fully shown and described therein, and constituting an invention independent of the invention claimed in said former application.

The object of the invention claimed herein 20 is to provide a simple, inexpensive and effective means for securing a tape, sometimes termed a tab end, to a bushing, so that it will be held in proper position to be easily handled by the operative who is to sew said 25 tab end to the garment to which the bushing is to be attached. Heretofore it has been the practice for the operative who is to do the sewing to also attach the tape to the bushing, which act involves a substantial 30 loss of time. By the present invention, one operative may rapidly thread many bushings with short lengths of tape, and the same will be so held that the two ends of the tape will be positioned correctly for the sewing 35 process to be performed later by other operatives who are relieved of the burden of the assembly work.

In the drawings: Figure 1 is a front view 40 of a construction embodying my invention. Fig. 2 is an edge view of the bushing illustrating the method of threading the tape therewith.

Fig. 3 is a plan view of the bushing.

1 represents a tubular bushing which is designed to receive and support a connector, 45 for example, a safety pin, the pin portion being indicated at 2 (see Fig. 1), the bushing serving to reinforce the pin so that it will not bend under strain. The form of said connector is, of course, immaterial. The 50 bushing 1 has an integral lateral offset plate or extension 3 which is slotted longitudinally so as to form the two spaced bars 4—5, these bars being properly spaced to permit the two 55 ends of a webbing to be tucked underneath the same as shown. 7 represents a strip of webbing which is to constitute the tab end. This webbing is folded around the bushing 1, and the two ends are tucked under the bars 4—5, the latter serving to hold the two 60 ends together as shown in solid lines in Fig. 2, so that the operative who is to sew or stitch the tab to a garment (a portion of which is indicated at 8) may pick up the tab with the two ends in position and sew it in 65 place. It is apparent that when these bushings and strips of webbing have been combined as shown in Fig. 2, it will operate greatly to the advantage of the manufacturer in the saving of time required to affix 70 the same to the garment. It is also apparent that when said parts are combined they will stay in place since said parts are so light that the frictional engagement between the same is relatively so great that accidental 75 disengagement will rarely if ever occur.

What I claim is:

In a device of the character described, a tubular bushing, a lateral extension from one side thereof, said extension being slotted to 80 form two bars, said bars being oppositely offset to provide a passage for the two ends of a supporting tape arranged to surround said bushing, said bars operating to hold together the projecting ends of such a tape. 85

WILLIAM S. HUNKINS.
